UNITED STATES PATENT OFFICE.

WALTER T. DAVIS, OF WHEELING, WEST VIRGINIA, ASSIGNOR TO WHEELING STAMPING COMPANY, OF WHEELING, WEST VIRGINIA, A CORPORATION OF WEST VIRGINIA.

CONTAINER AND CLOSURE THEREFOR.

Application filed April 4, 1923. Serial No. 629,846.

To all whom it may concern:

Be it known that I, WALTER T. DAVIS, a citizen of the United States, residing at Wheeling, in the county of Ohio and State 5 of West Virginia, have invented a new and useful Improvement in Containers and Closures Therefor, of which the following is a full, clear, and exact description.

The present invention relates broadly to 10 containers, and more particularly to collapsible containers of the type having a screw-threaded discharge neck adapted to be screwed into an opening through which it may be desired to discharge the contents of 15 the container.

The invention has particular significance 20 with respect to collapsible dispensing tubes of the type used for "Neverleak" and similar liquids which harden upon coming into contact with air. Such tubes are ordinarily provided with a threaded outlet neck adapted to be screwed directly into the valve stem of a pneumatic tire, and the contents of the tube discharged by merely collapsing the 25 tube. Containers of this character, as heretofore constructed, have had the cap for closing the discharge orifice during normal periods of handling held in position by the threads for engaging the valve stem. Frequently 30 the threads in the cap are not true, and they so distort the threads on the tube that the latter cannot be threaded into a valve stem.

The present invention is intended for the 35 purpose of overcoming the above difficulty. This is accomplished by so constructing the discharge neck of the container and the cap that the latter covers and protects the portion of the neck having the screw threads 40 thereon for engagement with the opening through which it is desired to discharge the contents of the tube without actually engaging said threads.

In the accompanying drawings, there is 45 shown, for purposes of illustration only, one embodiment of the present invention, it being understood that the drawings do not define the limits of the invention, as changes may be made in the construction therein 50 disclosed without departing from the spirit of the invention or scope of my broader claims.

In the drawings:

Figure 1 is a view in elevation of a container 55 having the discharge neck thereof

constructed in accordance with my invention, and illustrating the cap for cooperation with said neck, and

Figure 2 is a view showing the neck portion of the tube and the cap in section. 60

Referring to the drawings, A designates a collapsible tube having a discharge neck B, and C designates the cap for cooperation with said neck. In the form of the invention illustrated, the end portion b of said neck is screw-threaded for engagement with the opening through which it may be desired to discharge the contents of the tube, whereas the portion c of the neck, between said end portion and the body of the tube, 70 is of greater diameter than said end portion, and is also screw-threaded for engagement with the cap C.

The cap C is provided with internal screw threads for cooperation with the screw-threaded neck portion c, and is provided with a smooth bore adjacent said internal threads to receive the screw-threaded neck portion b without engaging the threads of said portion. Preferably, this smooth bore 75 of the cap will be formed of slightly greater diameter than the external diameter of said neck portion b. The cap may be provided with a conical projection d adapted to project into the discharge orifice of the tube 80 and seal the same when the cap is in operative position on the discharge neck B. 85

An important advantage of the present invention arises from the provision in a container of a cap for closing the discharge 90 neck thereof, which does not engage the threads of said neck intended for cooperation with the threads of the opening through which it may be desired to discharge the contents of the container. 95

A further advantage of the invention arises from the construction of the discharge neck of the container with a threaded end portion for cooperation with the opening through which it may be desired to discharge the contents of the tube, and with a portion of greater diameter than said threaded end portion for cooperation with a cap. 100

I claim:

1. A container provided with an integral discharge neck having a screw-threaded portion adapted to be screwed into an opening through which it may be desired to discharge the contents of the container and a 110

portion of greater diameter than said screw-threaded portion, and a cap constructed to cover said screw-threaded portion without engaging the threads of the same and to co-
5 operate with said portion of greater diameter to form a closure for said container, substantially as described.

2. A container provided with an integral discharge neck having a screw-threaded end portion adapted to be screwed directly into
10 an opening through which it may be desired

to discharge the contents of the container and having a screw-threaded portion adjacent thereto of greater diameter, and a cap internally screw-threaded for cooperation 15 with said screw-threaded neck-portion of greater diameter and constructed to cover said end portion without engaging the threads thereof, substantially as described.

In testimony whereof I have hereunto set 20 my hand.

WALTER T. DAVIS.
